CLAIM

The ornamental design for a cooling dock, as shown and described.

DESCRIPTION

FIG. 1 is a front, side and top perspective view of a cooling dock showing my new design;

FIG. 2 is a back, side and top perspective view thereof;

FIG. 3 is a front elevational view thereof;

FIG. 4 is a back elevational view thereof;

FIG. 5 is a left side elevational view thereof; The right side elevational view is a mirror image of the left side;

FIG. 6 is a top plan view thereof;

FIG. 7 is a front, side and top perspective view of a cooling dock showing my new design;

FIG. 8 is a back, side and top perspective view thereof;

FIG. 9 is a front elevational view thereof;

FIG. 10 is a back elevational view thereof;

FIG. 11 is a left side elevational view thereof; The right side elevational view is a mirror image of the left side; and,

FIG. 12 is a top plan view thereof.

The broken lines shown in the drawings show portions of the cooling dock that form no part of the claimed design.
